[75] Inventor: Gennard O. B. Mahl, San Francisco, Calif.

Primary Examiner—Wallace R. Burke

Assistant Examiner—B. J. Bullock

Attorney, Agent, or Firm—Phillips, Moore, Weissenger, Lempio & Majestic

[**] Term: 14 Years

[57] CLAIM

The ornamental design for a vacuum deposition apparatus, substantially as shown and described.

DESCRIPTION

FIG. 1 is a front and left side perspective view of my new vacuum deposition apparatus design with the unshown bottom being substantially plain and unornamented;

FIG. 2 is a top plan view thereof;

FIG. 3 is a side elevational view thereof, taken from the right side of FIG. 1.

FIG. 4 is a rear elevational view thereof.
